THERMOSTATIC SAFETY CONTROL SYSTEM
FOR GAS BURNERSWilliam A. Ray, Glendale, Calif., assignor to
General Controls Co., a corporation

Application February 28, 1944, Serial No. 524,212

13 Claims. (Cl. 158—117.1)

1 This invention relates to the operation of a gas furnace, such as may be used for heating a building, or a portion of a building.

It has been common to provide a pilot flame that is intended to be continuously active to ignite a main burner. The valve for the main burner is controlled, for example, by a thermostat. The valve is usually operated by an electromagnet, the circuit of which is energized and de-energized in accordance with the position of the thermostat.

In such systems, in the event the pilot flame is extinguished for any reason, provisions are made to ensure that the main valve to the burner remains closed until the pilot flame is re-established. Until that time, the heating system is shut down.

It is one of the objects of this invention to provide a heating system that obviates these disadvantages and that, nevertheless, ensures operation with safety, and with assurance against premature ignition of the main burner.

It is another object of this invention to cause automatic operation of the pilot burner in response to the operation of the controlling thermostat, and to ensure that the pilot burner can be lighted only upon the existence of safe conditions. In this way, the pilot burner is lighted only when the main burner is to be lighted.

It is another object of this invention to ensure that, before the pilot burner can be lighted, the danger of an explosion in the furnace chamber is eliminated. This is accomplished by ensuring that the supply of fuel to the pilot burner can occur only when certain conditions are fulfilled, such as that the supply of fuel to the main burner be substantially interrupted; that there be no failure in the control circuit, such as open circuits or short-circuits; that the igniter for the pilot burner is operative; and that a period of time sufficient to clear the furnace of an explosive mixture must elapse between successive attempts to ignite the pilot burner.

It is still another object of this invention to ensure that the main burner can be supplied with fuel only after the pilot burner valve is opened and the pilot burner is in operation.

It is still another object of this invention to ensure that, in the event of flame failure, the supply of fuel to the main burner is interrupted; and that the automatic re-ignition of the system can occur only after a definite period has elapsed to permit the furnace chamber to be cleared of an explosive mixture.

It is still another object of this invention to interrupt all flow of fuel in the event the pilot burner should fail to ignite after a definite time interval.

It is still another object of this invention to provide a fuel control mechanism, such as a

2 valve, in which circuit controlling devices are incorporated, whereby the mechanism serves not only to control the flow of fuel, but also as a relay.

5 It is still another object of this invention to provide a valve structure especially adapted to be used for controlling the supply of gaseous fuel to the main burner, and arranged so that it can substantially entirely cut off the supply of fuel, although the closure may be prevented by dirt, or the like, from closing entirely.

10 It is still another object of this invention to provide an electric circuit controlling device that functions effectively for the dual purpose of timing successive operations of the igniting system and of interrupting the flow of fuel in the event there is a failure to ignite the pilot burner.

15 This invention possesses many other advantages, and has other objects which may be made 20 more clearly apparent from a consideration of several embodiments of the invention. For this purpose there are shown a few forms in the drawings accompanying and forming part of the present specification. These forms will now be 25 described in detail, illustrating the general principles of the invention; but it is to be understood that this detailed description is not to be taken in a limiting sense, since the scope of the invention is best defined by the appended claims.

30 Referring to the drawings:

Figure 1 is a diagrammatic representation of a gas heating installation embodying the invention;

35 Fig. 2 is a sectional view of a valve for controlling the flow of fuel to the main burner of the system;

Fig. 3 is a sectional view of a valve for controlling the flow of fuel to the pilot burner that is used to ignite the main burner;

40 Fig. 4 is a diagrammatic view of a combination timer and safety switch mechanism utilized in the invention;

Fig. 5 is a wiring diagram of the system illustrated in Fig. 1, the system being inactive, and the main burner being extinguished;

45 Fig. 6 is a diagram similar to Fig. 5, but illustrating an intermediate stage of operation of the system;

Fig. 7 is a diagram similar to Fig. 5, showing the fully operative stage of the system; and

50 Fig. 8 is a view similar to Fig. 5, of a modified form of the invention.

In Fig. 1 there is shown a main burner 1 adapted 55 to be supplied with fuel through the pipe or conduit 2. The flow of fuel to the main burner is controlled by an electromagnetically operated valve 3, interposed in the conduit 2. This valve 3 is shown in greater detail in Fig. 2.

59 The inlet side of the valve is connected to a

pipe 4 that leads to an appropriate source of gaseous fuel.

For igniting the main burner 1, use is made of a pilot burner 5. This pilot burner 5 is shown as supplied with fuel through a conduit 6, also connected in an appropriate manner to the source of gaseous fuel. In the conduit 6 is interposed a pilot burner valve 7. This valve 7 is shown in greater detail in Fig. 3.

The heating system may be in the form of a furnace adapted to heat a space, such as a room or building. The main burner 1 is electrically controlled by aid of valve 3 so that it remains inactive until there is demand for additional heat. In this inactive stage the pilot burner 5 is also extinguished.

When conditions demand the lighting of the main burner 1, the controls operate in sequence to open the pilot burner valve 7 and to ignite the pilot burner by the aid of an igniter 8; and, as soon as the pilot burner 5 is in full operation, the main valve 3 is permitted to open, and the main burner 1 is ignited.

As soon as conditions demand that the main burner 1 be extinguished, the main valve 3 is closed and the pilot burner valve 7 is also closed. The system then is in its inactive condition.

The safeguards and protective devices incorporated in the system may be more readily explained in connection with Figs. 5, 6, and 7.

One of the important safety devices is an apparatus that responds to the heat of the pilot flame, and that is arranged to maintain the system inoperative unless the pilot flame is in existence. Such a safety device may, for example, include a thermostat adapted to be influenced by the heat of the pilot flame. In the present instance, however, use is made of a thermoelectric device, or thermocouple 9, indicated diagrammatically in Figs. 1, 5, 6, 7, and 8. The thermocouple is shown in Fig. 1 as being disposed close to the pilot burner 5 so as to be heated by the pilot flame.

The electrical energy generated by the thermocouple 9 is used to operate a safety relay 10 (Figs. 5 to 8 inclusive). The safety relay 10 is operated by the coil 11 of an electromagnet. While the pilot burner 5 is inactive, the coil 11 is de-energized and the armature 12 of the relay 10 is in the lowered or dropped position illustrated in Figs. 5, 6, and 8. When the pilot burner 5 is energized, the armature 12 moves to the attracted position of Fig. 7 by the electromagnet coil 11.

When this occurs, the main valve 3 is opened and the main burner 1 is rendered active. For operating the main valve, use is made of electromagnet M (see, also, Fig. 2) that, when energized, causes the valve 3 to open.

In the inactive or off position of Fig. 1, both main valve 3 and the pilot burner valve 7 are closed. The initiation of the operation of the system is dependent upon the operation of the switching device 13, which may be automatic, as a room thermostat.

In Fig. 5 the control circuits are shown as supplied with electric energy through a step-down transformer 14. While the switching device 13 is in open position, as illustrated in this figure, the control circuits are inactive. The relay 10 is de-energized and armature 12 is in a position such as to render the back contact 15 active.

When the switching device 13 is closed, as illustrated in Fig. 6, the control circuit is energized through the back contact 15 to cause the pilot valve 7 to open. This is caused by energization

of a section of the electromagnetic coil P that operates the pilot valve. The completion of this energizing circuit is dependent upon certain safety factors that must exist: Thus, the circuit for the coil P may be traced as follows: lead 16 from transformer 14, switching device 13, lead 17, a safety switch S₁, lead 18, armature 12, back contact 15, a safety heating device 19, the igniter 8, switch M₁, switch T₁ or P₃ which are in parallel, a section of coil P, to the transformer 14 by the other lead 25.

In order for this circuit to be energized, therefore, it is necessary that each and every one of the elements in series be capable of transmitting electrical energy; that is, the switch S₁ must be closed; the back contact 15 must be engaged by armature 12; the safety heater 19 must be in operative condition; the igniter 8 must be good; the switch M₁ must be closed; and either switch T₁ or switch P₃, or both, must be closed.

The switch M₁ is closed only when the main valve 3 is in substantially closed position, such as illustrated in Fig. 2. The manner in which this is effected will be described in connection with the description of the main valve 3.

The switch T₁ is operated to open and closed position by the flexure of a bimetallic bar 21 (Fig. 4). This switch closes only after a sufficient interval has elapsed to purge all unignited fuel from the furnace chamber; and the danger of an explosion is thus avoided. Its specific mode of operation will be described hereinafter.

The heater 19 is shown as a coil in Fig. 4 that is in heat transfer relation to the bimetallic bar 21. Upon an undue delay in the ignition of the pilot burner 5, this heating coil 19 causes the bar 21 to flex so far as to cause the safety switch S₁ to open.

However, assuming that the igniter 8 is good, and that the switches M₁ and T₁ are closed, the pilot burner valve 7 is opened by the energization of a section of the coil P.

Accordingly, the igniter 8 can then light the burner 5, and the pilot flame thereupon heats the thermoelectric device 9.

When the thermocouple 9 generates sufficient electrical energy to energize relay coil 11, the armature 12 is attracted to the position illustrated in Fig. 7. Accordingly, the front contact 22 is now engaged by the armature 12, and another control circuit, paralleling the first one described, is rendered active. This control circuit likewise energizes the pilot burner electromagnetic coil P. The movement of the armature 12 from the unattracted position of Figs. 5 and 6 to the attracted position of Fig. 7 is so rapid that the pilot burner valve 7 does not close before the second control circuit is energized.

The second control circuit may be traced from transformer 14 through lead 16, switching device 13, lead 17, safety switch S₁, lead 18, armature 12, front contact 22, a timer heater 23 in parallel with a timer switch T₂, a switch P₁, coil P, and to transformer 14 through lead 25. Accordingly, in order for this circuit to remain energized, it is necessary that the relay armature 12 be in attracted position; that is, that the pilot burner flame must be on. Furthermore, the switch P₁ must be closed. This switch P₁ is arranged to be closed only when the pilot burner valve 7 is open; in other words, if, for any reason, the pilot burner valve 7 should close, the switch P₁ would open and the control circuit just traced would be open-circuited. The timer heater 23 is shown

in Fig. 4 as also in heat transfer relation with the bi-metallic bar 21.

The energization of relay coil 11 also causes energization of the electromagnet M for main valve 3. This occurs by the aid of the additional front contact 24. The circuit for the coil M is then completed through lead 16 and switching device 13, lead 17, safety switch S1, lead 18, armature 12, front contact 24, coil M, and a switch P2. The switch P2, as shown in Fig. 3, is also arranged to be closed only in the event that the pilot burner valve 7 is open. Accordingly, the control circuit for the main valve 3 cannot be operated unless the safety switch S1 is closed, the thermocouple 9 is active, and the pilot burner valve is open, maintaining switch P2 closed. This running condition is shown in Fig. 7, the main burner then being lighted.

The main valve 3 is shown diagrammatically in Fig. 2. The valve includes a body 26. This body has a partition 27 separating the inlet 28 from the outlet 29. The partition 27 has a tubular port 30. The upper edge 31 of the port is formed as a narrow valve seat upon which the valve closure member 32 may rest.

The valve closure member 32 is in the form of a disc and is attached to a flexible diaphragm 33 that is disposed over the upper flange of the body 26. A stiffening washer 34 is disposed on the upper side of the diaphragm 33.

The closure member 32, the diaphragm 33, and the washer 34 are held together by the aid of a bolt 35. Furthermore, there is provided a supplemental closure 36 that is intended to telescope within the port 30. This closure 36 may be in the form of an inverted cup extending considerably below the main closure 32.

In the event the main closure 32 fails to seat accurately, the supplemental closure 36 nevertheless serves substantially entirely to interrupt the flow of fuel through the valve 3.

Operation of the valve is effected by the aid of fluid pressure. For this purpose, a chamber 37 is provided above the diaphragm 33, as by the housing 38. This housing 38 is supplemented by a sheet metal cover 39 sealed to the top of the housing 38 and serving to provide a sealed space above the diaphragm 33.

The diaphragm 33 may be urged downwardly to closed position by the fluid pressure existing in the intake side of the valve 26. This is accomplished by the aid of the passages 40 and 41, formed respectively in the body 26 and the housing 38. The outlet of passage 41 is connected to a jet member 42. Through the jet member, the fluid fuel passes into the chamber 37.

Should it be desired to open the valve, the jet member 42 is covered, and the chamber 37 is vented. This is accomplished by movement of an electromagnetic armature 43, shown as pivoted at 44. It is normally urged in a counter-clockwise direction, as by a spring 45, so that its lower end uncovers the jet 42. However, when the electromagnet M is energized, as heretofore described, the armature 43 is attracted against the force of the spring 45. In the attracted position, the armature covers the jet 42 and uncovers another jet 46 that is connected through a conduit 47 to the external atmosphere. In this way, the chamber 37 is vented and the inlet pressure on the lower side of the diaphragm 33 is sufficient to cause the valve to open.

The conduit 47, as shown most clearly in Fig. 1, may be led to the main burner 1 so as to cause

the fuel vented from chamber 37 to be harmlessly consumed.

As heretofore stated, opening of the valve 3 causes opening of the switch M1. This open position is illustrated in the running condition of Fig. 7, and ensures that only when the valve 3 is closed is it possible to open the pilot burner valve 7 and to energize the igniter 8.

The switch M1 is illustrated at the upper portion of Fig. 2. It includes the spring arms 87 and 88, insulated from each other and carrying the co-operating contacts 48 and 49. Normally, these spring arms are separated, so that the contacts 48 and 49 are open. However, when the valve 3 is closed, the contacts 48 and 49 are urged together by a spring arm 50 that is disposed above the spring arm 87. This spring arm 50 carries the abutment 51 engaging the upper arm 87. It is urged downwardly by the aid of a stem or rod 52 that is joined to the arm 50. The lower end of the stem 52 is connected to an intermediate point of a lever 54 pivoted on a bracket 55 in the housing 38. The extremity of the lever 54 is forked and is in sliding engagement with the reduced portion 56 of the bolt 35. The chamber 37 is maintained fluid tight in spite of the passage of the stem 52 out of the cover 39, as by the aid of the flexible bellows member 53. The switch M1 is enclosed in a cap 57.

Closing of the valve 3 by the exertion of fluid pressure above the diaphragm 33 thus serves, as well, to apply a force to the lever 54 which, in turn, pulls the stem 52 downwardly to close the switch M1.

The pilot burner valve 7 is shown in greater detail in Fig. 3. In this instance, the valve body 58 is shown as having a ported partition 59 that separates the inlet side 60 from the outlet side 61. The electromagnet, including the coil P, is supported in a housing 62 attached to a collar 63. This collar 63 is threaded in fluid tight relation into the top of the body 58.

The electromagnetic coil P operates upon a solenoid core 64 which is joined to the conical closure member 65. A light spring 66 exerts a force urging the closure member 65 downwardly against its seat. When the coil P is energized, the force of this spring is overcome, and the valve opens.

The switches P1, P2, and P3, which are operated in accordance with the operation of valve 7, are arranged below the body 58 and are shown as enclosed in a casing 67. This casing 67 is supported on the threaded shank 68 that is accommodated in the lower portion of the valve body 58. The lower contacts 69, 70, and 70—a of the switches P1, P2, and P3, respectively, are carried on a support 71. This support is mounted on the bottom of a movable stem 72 which is guided in the shank 68. The upper end of the stem cooperates with the lower surface of closure 65. When the closure 65 is in place on its seat, it urges the stem 72 downwardly against the pressure of the spring 73 to open the switches P1, P2, and P3.

The co-operating upper contacts 74, 75, and 75—a of the switches P1, P2, and P3 are supported upon a plate 76. This plate 76 is resiliently supported upon a plurality of spring mounts 77. The co-operating contacts of the switches P1, P2, and P3 can thus readily accommodate themselves to provide effective contacting areas.

While the electromagnetic coil P is deenergized, the switches P1, P2, and P3 are in the posi-

tion shown. When the core 64 is lifted to open the valve, the spring 73 causes the stem 72 to rise and to bring contacts 69, 70, and 70—a against the contacts 74, 75, and 75—a respectively.

The coil P is shown as having two sections. Only one section is energized when the first control circuit is active, as shown in Fig. 6. When the armature 12 is raised to the active position of Fig. 7, the control circuit for the valve 1 is such that all of the turns of coil P are active. The difference in the number of turns that are active in the two control circuits is provided in order to equalize the electromagnetic force exerted by the coil P when either control circuit is active.

The timer device diagrammatically illustrated in Fig. 4 is provided to open the safety switch S₁ in the event that the pilot burner 5 fails to ignite after an interval. It also serves to operate the contacts forming switch T₁ which ensures against completion of the igniter circuit until a definite time has elapsed after burner 1 is extinguished, thereby preventing explosions of unconsumed fuel in the chamber.

This combination switch includes the bi-metallic bar 21 heated by the safety heater 19, as well as by the timer heater 23. The bar 21 carries an actuator 78 at its free end. This actuator 78 has two operating portions 79 and 80. The operating portion 79 serves to operate the switch T₂ formed by the flexible or spring arms 81 and 82. The switch T₂ is used alternately to short-circuit the heater 23 and to cause operation of the heater 23 for the purpose of keeping the bi-metallic bar 21 in a normally heated condition while the main burner 1 is on.

For this purpose, the lower arm 82, when bar 21 is cold, rests upon the portion 79. The switch T₂ is then open. Accordingly, when the circuit is otherwise completed, the timer heater 23 is active; and, after an interval, the bar 21 flexes sufficiently to close the switch T₂, immediately short-circuiting the heater 23. After a time, the bar 21 cools off and flexes downwardly, opening the switch T₂. This then re-energizes the heater 23 and the cycle is repeated. In this manner, the bi-metallic bar 21 is kept at an average flexure, between the limits required to open and close the switch T₂.

The flexure of the bar 21, corresponding to this normal operation, is sufficient to keep the switch T₁ continuously open. This is accomplished by proper choice of spacing of the contacts of switch T₁ with respect to the actuator 78. Switch T₁ is shown as formed by the flexible arms 83 and 84, upon which the switch contacts are mounted.

Accordingly, should there be a flame failure, the switch T₁ will not close until the bar 21 cools. The period of cooling is so fixed as to ensure that any accumulated gases in the furnace chamber will have been dissipated.

After the automatic switching device 13 is closed and the first control circuit, including the igniter 8, is completed through the safety switch S₁, as illustrated in Fig. 6, the proper operation of the system requires that the pilot burner 5 be lighted. This stage must occur while the circuit is in the condition of Fig. 6. In the event the pilot burner fails to ignite after a sufficient period, the safety switch S₁ is caused to open, and this switch stays open until it is manually closed.

For this purpose, the switch S₁ as shown in Fig. 4 is held in closed position by the member 78, the flexible arm 85 of the safety switch S₁ be-

ing thereby held in a flexed position. It is only upon extended flexing of the bar 21, due to continued heating by the heater 19, that the member 78 moves upwardly out of the path of the arm 85. Under such circumstances, arm 85 is free to move to the left, and switch S₁ opens. The entire system is thus rendered inoperative. Furthermore, since the top of the spring arm 85 then projects underneath the member 78, the switch S₁ cannot again close until the arm 85 is flexed to the right. This may be accomplished by the aid of a push button 86. The arrangement may be such, as is well understood, that this push button cannot operate the arm 85 until conditions are normal.

A complete résumé of the operation of the system may now be set forth. The normal inactive position is shown in Fig. 5. In this position, the automatic switching device 13 is inactive. The timer having cooled off, the timer switch T₁ is closed. Since the switch 13 serves to disconnect the transformer 14 from all of the control circuits, the electromagnetically operated main valve 3 is closed; and, accordingly, the switch M₁ is likewise closed. Similarly, since the pilot burner valve 7 is likewise inactive, the switches P₁, P₂, and P₃ are open; and, lastly, the armature 12 of relay 10 is in the lower or dropped position.

Furthermore, it is assumed that the safety switch S₁ has been placed in the closed position.

Now, in the event the switch device 13 closes, the first step after it is closed is illustrated in the intermediate position of Fig. 6. The first control circuit, including the igniter 8 and a section of the coil P, is energized through the closed switches T₁ and M₁. As soon as this energization takes place, the switch P₃ acts to short-circuit the switch T₁. This short-circuiting is essential, for the switch T₁ will soon open under the influence of the heating produced by the safety heating coil 19. Thus, the control circuit would open even before the thermocouple 9 could generate sufficient electric energy to energize coil 11, causing the armature 12 to move to its upper position and energize coil P through the circuit which includes contact 22.

The control circuit corresponding to the lower or unenergized position of armature 12, remains active until the pilot burner 5 is lighted and the thermocouple 9 is active to energize coil 11. If this takes an unduly long time, the safety switch S₁ opens by virtue of the extreme flexure of the bi-metallic bar 21 under the influence of safety heater 19.

Assuming, however, that the pilot burner 5 is ignited and that the thermocouple 9 is active, the running stage of operation is reached and is indicated by Fig. 7. In this stage, the armature 12 is attracted to its upper position, causing de-energization of the igniter 8. The closing of the front contacts 22 and 24, respectively, maintains the pilot burner valve 7 open, thus holding switches P₁, P₂, and P₃ closed, and causes the main valve 3 to open, thus opening switch M₁. These conditions exist until the automatic switching device 13 is moved to the open position. When this happens, the armature 12 drops and eventually the system reaches the condition of Fig. 5.

In the event of flame failure, the armature 12 would drop from the active position of Fig. 7, due to the cooling of thermocouple 9. This de-energizes coil M, allowing main valve 3 to close, as well as de-energizing coil P by breaking the circuit in-

cluding contact 22. The pilot burner valve 1 closes more rapidly than the main valve 3 due to the diaphragm 33 in the latter; hence switch P_3 is open before M_1 closes. Accordingly, neither energization of the igniter 8, nor opening of the pilot burner valve 1, can occur until bar 21 cools sufficiently to close switch T_1 , as shown in Fig. 5. This period is chosen to be sufficient to ensure that the furnace chamber is freed of any explosive unconsumed fuel mixture.

Thus, reviewing, upon flame failure, although the back contact 15 would be made quite rapidly, and switch T_1 would be temporarily bypassed by switch P_3 , switch M_1 would still be open because main valve 3 was not closed. But, if main valve 3 was not open, switch M_1 accordingly being closed, it would be satisfactory to energize the igniter 8, since, under these conditions, there would be no destructive volume of gas in the furnace.

The system is safeguarded in numerous ways. Any accidental mechanical failure, such as a break in any of the leads, or in any of the electrical elements, would cause the system to return to the inactive position of Fig. 5. Between the period of activity, the pilot burner valve must be closed, and the igniter 8 is inactive. It is only upon the energization of the system by closing of the switch 13 that it is possible to start the sequence of operations heretofore described. This sequence must occur in a definite pattern; and, if it does not, the system again must return to the inactive position of Fig. 5.

In the form of the invention illustrated in Figs. 5, 6, and 7, the main valve electromagnet M is shown as controlled by a separate front contact 24. However, it is possible to place the main electromagnetic coil M directly in parallel with the relay coil 11. Such a modification is illustrated in Fig. 8. The circuit for the coil M then includes thermocouple 9, as well as the switch P_2 that is closed only when the pilot burner valve 1 is open. Thus, in this case, the main valve is directly under the control of thermocouple 9. This provides an added safety factor.

The inventor claims:

1. In a gas heating system including a pilot burner: an electrically operated valve for controlling the flow of fuel to the pilot burner; a pair of control circuit means for independently operating said valve; means responsive to the existence or non-existence of a flame at the pilot burner for rendering one or the other of the circuit means capable of functioning; that one of said circuit means, which is capable of functioning when there is no flame issuing from the pilot burner, including an igniter in series in the circuit; and the other of said circuit means, which is capable of functioning when a flame is issuing from the pilot burner, including a switch in series in the circuit; and means closing said switch only when the pilot burner valve is open.

2. In a gas heating system including a pilot burner: an electrically operated valve for controlling the flow of fuel to the pilot burner; a pair of control circuit means for independently operating said valve; and means responsive to the existence or non-existence of a flame at the pilot burner for rendering one or the other of the circuit means capable of functioning; that one of said circuit means, which is capable of functioning when there is no flame issuing from the pilot burner, including an igniter in series in the circuit, as well as a timer switch; and the other of said circuit means, which is capable of

functioning when a flame is issuing from the pilot burner, including a timing device in series in the circuit for operating said timer switch for causing it to open; said timer switch being so constructed as to remain open for a time after the pilot burner flame is extinguished.

3. In a gas heating system including a main burner and a pilot burner: an electrically operated valve for controlling the flow of fuel to the pilot burner; a pair of control circuit means for independently operating said valve; means responsive to the existence or non-existence of a flame at the pilot burner for rendering one or the other of the circuit means capable of functioning; that one of said circuit means, which is capable of functioning when there is no flame issuing from the pilot burner, including an igniter in series in the circuit, as well as a switch that is closed only while there is an insubstantial supply of fuel to the main burner; means for supplying fuel to the main burner; and circuit means for causing fuel to be supplied to the main burner by said fuel supply means, and capable of functioning only while a flame is issuing from the pilot burner.

4. In a gas heating system including a main burner and a pilot burner: an electrically operated valve for controlling the flow of fuel to the pilot burner; a pair of control circuit means for independently operating said valve; means responsive to the existence or non-existence of a flame at the pilot burner for rendering one or the other of the circuit means capable of functioning; that one of said circuit means which is capable of functioning when there is no flame issuing from the pilot burner, including an igniter in series in the circuit means, as well as a safety switch, and a heater for the safety switch that eventually causes the safety switch to open in the event the pilot burner flame fails to be ignited, the failure to ignite thus causing the means responsive to pilot burner operation to maintain said one of said circuit means in a condition capable of functioning; the other of said control circuit means including a series switch that is closed in response to the opening of the pilot burner valve.

5. In a gas heating system including a main burner and a pilot burner: relay means including a movable member; means responsive to the heat of the flame issuing from the pilot burner for controlling said relay means, said relay means having front and back contacts adapted to be engaged, respectively, by said member in accordance with the existence and the non-existence of a pilot flame; an electrically operated valve for supplying fuel to the pilot burner; a first control circuit means which, when energized, causes said valve to open, said first control circuit means being in series with the back contact and including in series an igniter for the pilot burner as well as means for operating said pilot burner valve; a second control circuit means which, when energized, causes said valve to be maintained in open position, said second control circuit means being in series with the front contact; and electrically operated valve means for supplying fuel to the main burner and operative in response to the energization of said relay means.

6. In a gas heating system including a main burner and a pilot burner: relay means including a movable member; means responsive to the heat of the flame issuing from the pilot burner for controlling said relay means, said relay means

having front and back contacts adapted to be engaged, respectively, by said member in accordance with the existence and the non-existence of a pilot flame; an electrically operated valve for supplying fuel to the pilot burner; a first control circuit means which, when energized, causes said valve to open, said first control circuit means being in series with the back contact and including in series an igniter for the pilot burner as well as means for operating said pilot burner valve; a second control circuit means which, when energized, causes said valve to be maintained in open position, said second control circuit means being in series with the front contact; electrically operated valve means for supplying fuel to the main burner and operative in response to energization of said relay means; and a safety switch in series with that control circuit means of which the contact is engaged by said member, as well as with the electrically operated valve means for supplying fuel to the main burner; said first control circuit means including in series, a safety switch heater that causes said safety switch to open in the event said first control circuit means remains energized for a period of time.

7. In a gas heating system including a main burner and a pilot burner: relay means including a movable member; means responsive to the heat of the flame issuing from the pilot burner for controlling said relay means, said relay means having front and back contacts adapted to be engaged, respectively, by said member in accordance with the existence and the non-existence of a pilot flame; an electrically operated valve for supplying fuel to the pilot burner; a first control circuit means which, when energized, causes said valve to open, said first control circuit means being in series with the back contact and including in series an igniter for the pilot burner as well as means for operating said pilot burner valve; a second control circuit means which, when energized, causes said valve to be maintained in open position, said second control circuit means being in series with the front contact; said first control circuit also including in series a timer switch; said second circuit means including in series a heater that causes the timer switch to open, and that permits the timer switch to be closed only upon cooling sufficiently.

8. In a gas heating system including a main burner and a pilot burner: relay means including a movable member; means responsive to the heat of the flame issuing from the pilot burner for controlling said relay means, said relay means having front and back contacts adapted to be engaged, respectively by said member in accordance with the existence and the non-existence of a pilot flame; an electrically operated valve for supplying fuel to the pilot burner; a first control circuit means which, when energized, causes said valve to open, said first control circuit means being in series with the back contact and including in series an igniter for the pilot burner as well as means for operating said pilot burner valve; a second control circuit means which, when energized, causes said valve to be maintained in open position, said second control circuit means being in series with the front contact; electrically operated valve means for supplying fuel to the main burner; a third control circuit means adapted to be energized in response to the energization of said relay means, and which, when energized, operates the main valve; said first control circuit means including in series

a timer switch, a switch closed during unsubstantial supply of fuel to the main burner, and means forming a relay, having a coil in series in the said first control circuit means for short-circuiting said timer switch, said second control circuit means including in series, a switch closed when the pilot burner valve is open, and a heater for the timer switch that, when heated, causes the timer switch to open and to remain open; said electrically operated valve means for supplying fuel to the main burner including an energizing circuit in which there is a series switch operated to close position when the pilot burner valve is open; and a safety switch in series with those control circuit means in condition to be energized; said first control circuit means including a heater for the safety switch that causes the safety switch to open after the first control circuit means is energized for an interval.

9. In a gas heating system including a main burner and a pilot burner; a relay having an operating coil, front and back contacts and a member movable in response to energization and de-energization of said coil and adapted to engage respectively said contacts; means responsive to the heat of the flame issuing from the pilot burner for energizing said coil; said front and back contacts being engaged respectively by said member in accordance with the existence and the non-existence of a pilot flame; an electrically operated valve for supplying fuel to the pilot burner; a first control circuit means which, when energized, causes said valve to open, said back contact being in series with said first control circuit and including in series an igniter for the pilot burner; a second control circuit means which, when energized, causes said valve to be maintained in open position, the front contact of the relay being in series with said second control circuit; an electrically operated valve means for supplying fuel to the main burner; and a circuit parallel to the relay coil for energizing said valve means.

10. In a gas heating system having a pilot burner: an electrically operated valve for controlling the flow of fuel to the pilot burner; a first control circuit means for said valve, including a timer switch and a time delay mechanism for operating said switch; means for igniting the pilot burner; and a second circuit means responsive to the ignition of the pilot burner for opening said first control circuit when the pilot burner is ignited, said mechanism having electrical means included in said second circuit means for keeping the said switch open for an interval after the pilot burner is extinguished.

11. In a gas heating system having a pilot burner: an electrically operated valve for controlling the flow of fuel to the pilot burner; a control circuit means for said valve, including a timer switch and an electrically energized igniter in series; heater means operated in response to energization of said circuit for a period to open said switch; and circuit means for short-circuiting the timer switch, comprising a circuit controller paralleling said switch, a heater having a coil in series with said circuit controller for maintaining said switch open for an interval after said circuit means becomes inactive, and means controlling the energization of the heater coil in response to variation in temperature at the coil for maintaining said temperature between limits.

12. In a heating system utilizing fluid fuel, and having a main burner and a pilot burner; an

electrically operated valve controlling the passage of fuel to the pilot burner; and means for reducing the supply of fuel to the main burner to an insubstantial degree before the pilot burner valve may be opened, comprising a valve for the main burner, said main burner valve having a movable closure; means for moving said closure between open and closed positions; circuit means for operating the pilot burner valve; and a controlling device for said circuit means, and operated by movement of the closure toward closing position.

13. In a gas heating system having a pilot burner: an electrically operated valve for controlling the flow of fuel to the pilot burner; a control circuit through which the valve may be electrically operated when the circuit is completed for opening the valve; said circuit including an electrically energizable igniter for the burner; a time delay switch means having contacts and electrically energized contact operating means, both the contacts and contacting operating means being included in said circuit and operating to open the circuit after an interval of energization of the igniter; and a sec-

5

ond circuit means operating to maintain the pilot valve open upon ignition of the pilot flame.
